[54] PROCESS TO REDUCE PILLING OF POLYESTER KNIT FABRICS**[76] Inventor: Stephen Bass, 2302 Riddle Ave.,
Wilmington, Del. 19806****[21] Appl. No.: 69,232****[22] Filed: Aug. 23, 1979****[51] Int. Cl.² ..... D01C 1/00****[52] U.S. Cl. ..... 8/139****[57] ABSTRACT**

The pilling propensity of knit fabric from polyester staple fiber can be reduced by scouring the fabric at a temperature in the range of about 160° to 205° F. for from about 15 to 60 minutes in a 0.3 to 1.0% aqueous caustic solution containing about 0.001 to 0.1% of a quaternary ammonium salt of the formula:

wherein R is an alkylene radical of 2 to 3 carbon atoms, R' is H or phenyl, R'' is a C₁₂-C₁₈ hydrocarbon radical, x is 2 or 3, y is 0 to 3, and Z⁻ is an anion, preferably the dimethyl sulfate quaternary ammonium salt of bis(hydroxy-tri-1,2-propyleneoxy-2-ethyl)taallowamine. After scouring, the fabric is normally rinsed, neutralized, rinsed again and dried.
